UNITED STATES PATENT OFFICE.

GEORGE H. GILLETTE, OF NEW YORK, N. Y., ASSIGNOR TO GILLETTE SAFETY RAZOR COMPANY, A CORPORATION OF MASSACHUSETTS.

SAFETY-RAZOR.

1,141,183.

Specification of Letters Patent. Patented June 1, 1915.

Application filed May 3, 1911. Serial No. 624,837.

To all whom it may concern:

Be it known that I, GEORGE H. GILLETTE, a citizen of the United States, and resident of the borough of Manhattan, city, county, and State of New York, have invented certain new and useful Improvements in Safety-Razors, of which the following is a specification, reference being had to the accompanying drawings.

10 My invention relates to safety razors of that type in which the blade is held in place by spring pressure, and has as its principal object to provide a simple and inexpensive razor having means for readily adjusting 15 the cutting edge of the blade with respect to its distance from the guard and for securely retaining the blade in operative position, the features of construction and arrangement whereby this object is attained being 20 hereinafter described in detail and specified in the claims.

In the drawings Figure 1, is a back view of one form of embodiment of the improvements; Fig. 2, is a plan view thereof, and 25 Fig. 3, a side view of the same. Fig. 4, is a side view of another form of embodiment; Fig. 5, is a section on the line 5; 5, of Fig. 4, and a plan of the parts below that line. Fig. 6, is an enlarged side view partly in 30 section, but showing the adjusting device in full, the form being the same as in Figs. 4, and 5.

In Figs. 1, 2, and 3, of these drawings *a*, represents the handle, which is shown corrugated or fluted in a well known way, but 35 its exterior surface may be plain, or it may be made with any style of configurations which pleases the fancy. The small end *b*, of the handle *a*, is joined or secured by 40 solder or otherwise to the middle of the base *c*, of the holder, which, as shown, has its front edge formed into a guard or guard-teeth *d*, the extreme front ends *e*, *e*, being wider than the teeth for the purpose of receiving the sharp edge corners of the blade and protecting the face against cutting. 45 The back *f*, of the holder, is bent up at an angle to the base on which the handle is joined, and this back part *f*, also has a bend 50 or angle *g*, which forms a rest for the back of the blade. As shown the same piece of metal has an opening in it above and in front of the blade rest *g*. The opening is 55 surrounded by the back and by end pieces *h*, *h*, and a front piece or clamp *i*, the end

and front pieces being bent and curved over in such a way as to form a spring and clamp on the blade *j*, near its cutting edge and over the guard teeth. The back of the blade *j*, is shown as having a U-shaped stiffener 60 *k*, such as commonly belongs to or forms a part of blades of the style shown. The stiffener *k*, seats in the angle rest *g*, and the end pieces *h*, *h*, press on the front of the stiffener so as to keep the blade back in 65 the rest, while the front part or clamp *i*, presses the blade down near the cutting edge. Thus, the blade is kept firm in its place and firm at its edge. The back *f*, of the holder is provided with a collar or stud 70 *l*, secured thereto by solder or otherwise, and a threaded opening is made through this stud and the back *f*, for receiving a screw *m*, having its outer end terminating in a collar or stud *n*, joined to a milled head 75 *o*, for permitting it to be turned by thumb and finger. The threads on the screw *m*, terminate near its inner or free end which is beveled or rounded and bears against the under side of the blade *j*, so as to press the 80 blade up against the clamp *i*, which will yield as the blade is pressed away from the guard teeth or raised by the screw.

In the form of embodiment shown by Figs. 4, 5, and 6, the structure is essentially 85 the same as to the handle *a*, its small end *b*, holder-base *c*, guard-teeth *d*, corner supports *e*, *e*, back *f*, bend or blade rest *g*, end pieces *h*, clamp *i*, of the spring, blade *j*, and the 90 blade stiffener *k*. In this form of embodiment, however, the handle *a*, has a milled head *o'*, at its larger or outer end, and an inside collar or stud *l'*, from which a shaft *m'*, extends on the inside of the handle to and through the holder *c*, and the shaft *m'*, 95 also has an oval shaped shank or pin which after passing through a wedge or cam *n'*, is headed or secured like a rivet. In this instance the milled head *o'*, may be turned by thumb and finger so as to rotate the shaft 100 *m'*, and also the cam or wedge *n'*, which is thereby made to act on the under side of the blade, the latter pressing against the spring as the cutting edge is raised from the guard teeth.

In the structure shown by all figures, the adjustment or the raising and lowering of the cutting edge is positive and sure, and can be made to a nice degree according to the requirements of the user as to closeness 110

of shave. The rotary movement of the screw or shaft, may be the smallest part of a turn, or several full turns may be made in the screw adjustment, or a half turn made 5 in the wedge or cam adjustment, the extreme lift with the latter being shown on an exaggerated scale by the enlarged view of Fig. 6.

The improvement admits of considerable 10 modification or variation in the details of the precise means used for producing a rising pressure on the blade, and a like blade pressure on the retaining spring. The form of the holder and spring may also be modified, that shown being intended to illustrate 15 a cheap form of guard, holder, and spring made of a single piece of metal. The integrally formed holder, guard and spring, has some special utilities, but the adjusting 20 devices may also be used with other spring retained blades.

Having thus described my invention, what I claim as new and desire to secure by Letters Patent is:—

25 1. A safety razor comprising a thin blade provided at its rear edge with a stiffening piece, a handle, and a blade holding head having a base portion rigidly secured to one end of the handle and provided at its front 30 edge with a guard, a rear portion extending upwardly behind the rear edge of the blade and provided with a shoulder forming a seat for the same, and a spring portion extending forwardly over said stiffening piece 35 and thence downwardly into position to engage the front portion of the blade and press its cutting edge toward the guard, said spring portion being shaped to make contact with the front edge of the stiffening piece

and thereby prevent forward movement of 40 the blade.

2. A safety razor comprising a thin blade provided at its rear edge with a stiffening piece, a handle, and a blade-holding head having a base portion rigidly secured to one 45 end of the handle and provided at its front edge with a guard, a rear portion extending upwardly behind the rear edge of the blade and provided with a shoulder forming a seat for the same, and a spring portion extending forwardly over said stiffening piece and thence downwardly into position to engage the front portion of the blade and press its cutting edge toward the guard, said spring portion being shaped to make contact with 50 the front edge of the stiffening piece and thereby prevent forward movement of the blade, and means for lifting the cutting edge of the blade from the guard to adjust the distance between them. 55

3. In a safety razor, a handle member and a blade holder, the said blade holder being rigidly mounted on said handle, a blade mounted in said holder, a guard, and means carried by the handle member for directly 65 engaging the blade intermediate its ends to adjust the cutting edge in a direction away from the guard, said means comprising a rotatable stem mounted in said handle and a head carried by said stem, said head being 70 formed with a cam surface which upon rotation of the stem varies the distance of the cutting edge of the blade from the guard by the pressure of the head against the blade.

GEORGE H. GILLETTE.
